UNITED STATES PATENT OFFICE

109,699

DESIGN FOR A FACE PLATE FOR OVEN THERMOMETERS

George J. Day, Buffalo, N. Y.

Application March 19, 1938, Serial No. 75,973

Term of patent 7 years

To all whom it may concern:

Be it known that I, George J. Day, a citizen of the United States, residing at Buffalo, in the county of Erie and State of New York, have invented a new, original, and ornamental Design for a Face Plate for Oven Thermometers, of which the following is a specification, reference being had to the accompanying drawing, forming a part thereof.

Figure 1 is a front view of the face plate em-

bodying my design. Figure 2 is a top plan view thereof. Figure 3 is an end view of the same. Figure 4 is an enlarged longitudinal section taken substantially in the plane of line 4—4, Figure 1. Figure 5 is an enlarged cross section taken on line 5—5, Figure 1.

I claim:

The ornamental design for a face plate for oven thermometers, substantially as shown.

GEORGE J. DAY.
